UNITED STATES PATENT OFFICE.

CARL C. MADSEN AND JESS A. KALTOFT, OF RUTHTON, MINNESOTA.

JACK.

Application filed October 11, 1924. Serial No. 743,047.

To all whom it may concern:

Be it known that we, CARL C. MADSEN and JESS A. KALTOFT, citizens of the United States, residing at Ruthton, in the county 5 of Pipestone and State of Minnesota, have invented certain new and useful Improvements in Jacks, of which the following is a specification, reference being had to the accompanying drawings.

- 10 This invention relates to certain improvements in jacks and has relation more particularly to a device of this general character especially designed and adapted for use in connection with motor driven vehicles 15 and it is an object of the invention to provide a jack constructed in a novel and improved manner whereby a relatively low frame may be employed and at the same time permitting an effective lift of the car.
- 20 Another object of the invention is to provide a novel and improved device of this general character which may be employed to advantage in connection with an axle of a motor driven vehicle or the like which is 25 positioned unusually low.

The invention consists in the details of construction and in the combination and arrangement of the several parts of our improved jack whereby certain important advantages are attained and the device rendered simpler, less expensive and otherwise more convenient and advantageous for use, as will be hereinafter more fully set forth.

The novel features of our invention will 35 hereinafter be definitely claimed.

In order that our invention may be the better understood, we will now proceed to describe the same with reference to the accompanying drawings, wherein:—

40 Figure 1 is a view in elevation illustrating a jack constructed in accordance with an embodiment of our invention;

Figure 2 is a vertical sectional view of the device as illustrated in Figure 1;

45 Figure 3 is a view partly in elevation and partly in section of the device as herein disclosed, the line of section being substantially at right angles to that of Figure 2;

Figure 4 is a view partly in top plan and 50 partly in horizontal section of the device as herein disclosed;

As disclosed in the accompanying drawings, B denotes the base or frame of our improved jack which is relatively low. The 55 base B comprises a cylindrical body 1 provided at its lower end with a supporting

plate 2 herein disclosed as integrally formed therewith.

The opposite or upper end of the cylindrical body 1 is closed by the head or plate 3 60 partially extending within the body 1 and held or locked in applied position by the screw 4 or its equivalent.

The central portion of the head or plate 3 has threaded therethrough the tubular 65 jack screw 5 the lower end portion of which being defined by an outstanding flange 6 fitting within an upstanding annular holding flange 7 carried by the plate 8. The flanges 6 and 7 coact in a manner to effect a 70 swiveled connection between the stem 5 and the plate 8.

The plate 8 is non-rotatable and as herein set forth is held against rotation by the diametrically opposed pairs of ears 9 each pair 75 of which receiving therebetween a rib 10 carried by the inner wall of the cylindrical member 1. While the ears 9 coact with the ribs 10 to hold the plate 8 against rotation yet no hindrance or obstruction is offered to 80 the movement of the plate 8 lengthwise of the body 1 as the jack screw 5 has longitudinal movement in either direction.

The bore of the jack screw 5 is interiorly threaded, said interior threads 12 being reversed with respect to the exterior threads 14. In threaded engagement with said interior threads 12 through the outer end of the jack screw 5 is an outer or upper jack screw 15. The outer extremity of the screw 90 15 is provided with the lifting head or rest 16 which may be formed or designed as desired. Fixed to the plate 8 at the axial center thereof is an upstanding bar or post 17 angular in cross section and of desired 95 length. The upper or outer end portion of which being received within the bore 18 of the jack screw 15 said bore being of substantially the same cross sectional configuration as that of the bar or post 17. This 100 bar or post 17 operates to hold the jack screw 15 against rotation so that as the screw 5 is rotated in one direction the screw 15 will be caused to have longitudinal movement in the same general direction as the 105 longitudinal movement of the screw 5.

It is to be noted that the bar or post 17 terminates a distance inwardly of the outer end of the screw 5 so that upon outward movement of the screw 15 a predetermined 110 distance, the bar or post 17 will be disengaged from the screw 15. By this means

2
it is assured that the screw 15 will not accidentally separate from the screw 5.

The screw 5 is provided therealong with a longitudinal guideway 19 in which is received an inwardly directed lug 20 carried by the annular gear 21, said gear being arranged within the cylindrical body 1 of the base B. By this mounting of the gear 21 the screw 5 may be readily rotated and at the same time be capable of the requisite endwise movement. The gear 21 is positioned above and operatively engaged with a second gear 22 which is properly positioned with respect to the gear 21 through an opening 23 provided in an upper portion of the wall of the body 1. This gear 22 is carried by a shaft 24 rotatably supported by the bearing 25. This bearing 25 is comprised in an arm 26 supported by the body 1 and disposed across the opening 23. The outer end portion of the shaft 24 is provided with a notched wheel 27 with which coacts in a well-known manner the ratchet lever 28 whereby the gear 22 may be rotated in either direction as the occasions of practice may necessitate.

A jack constructed in accordance with an embodiment of our invention is particularly adapted for use in connection with motor driven vehicles and especially where the axle is unusually low and while the base or frame B is materially low in size yet the screws 5 and 15 cooperate to effect a high lift.

From the foregoing description it is thought to be obvious that a jack constructed in accordance with our invention is particularly well adapted for use by reason of the convenience and facility with which it may be assembled and operated, and it will also be obvious that our invention is susceptible of some change and modification without departing from the principles and spirit thereof and for this reason we do not wish to be understood as limiting ourselves

to the precise arrangement and formation of the several parts herein shown in carrying out our invention in practice except as hereinafter claimed.

We claim:—

A jack comprising, in combination, a tubular base having its upper end open and provided in its side wall with an opening, an arm supported by the base exteriorly thereof and disposed across the opening, a head closing the open end of the base, a tubular jack screw threaded through said head, a plate in swiveled connection with the inserted end portion of the jack screw, co-acting means carried by said second named plate and the wall of the member for holding the plate against rotation independently of the member, a second jack screw threaded into the first jack screw through the outer end thereof, said second jack screw having its inserted portion provided with a bore, an upstanding post carried by the second plate and extending within the bore of the second jack screw, said post and bore being angular in cross section to hold the second jack screw against rotation when the post is engaged within the bore of said second jack screw, said post having its upper end terminating inwardly of the outer end of the first named jack screw, a gear within the first member and surrounding said first named screw, means for keying said gear to the first named screw for rotation with said screw but permitting said screw to run therethrough, a gear rotatably supported by the arm extending across the opening in the side wall of the first named member and in mesh with the first named gear, and means for rotating the second named gear in either direction.

In testimony whereof we hereunto affix our signatures.

CARL C. MADSEN.
JESS A. KALTGFIT.
